UNITED STATES PATENT OFFICE.

THEODORE D. PALMER, OF SYRACUSE, NEW YORK, ASSIGNOR TO T. D. PALMER COMPANY, OF SYRACUSE, NEW YORK, A CORPORATION.

GARMENT-PRESSING MACHINE.

1,105,530.

Specification of Letters Patent. Patented July 28, 1914.

Application filed January 30, 1911. Serial No. 605,575.

To all whom it may concern:

Be it known that I, THEODORE D. PALMER, of Syracuse, in the county of Onondaga, in the State of New York, have invented new and useful Improvements in Garment-Pressing Machines, of which the following, taken in connection with the accompanying drawings, is a full, clear, and exact description.

This invention relates to certain improvements in garment pressing machines of the class set forth in my pending application #447,776 filed August 10, 1908 in so far as it makes use of two coacting pressing elements, commonly termed a "buck" and a "press head," one of which, in this instance the press head, is hinged to a suitable frame and adapted to be moved toward and from the buck to subject the garment to direct mechanical pressure as distinguished from sad irons and similar apparatus in which the garment is subjected to rubbing pressure. The pressing elements are preferably of sufficient size or area to press trousers, skirts, coats and similar garments throughout their entire lengths in a single operation and are therefore elongated in one direction and usually tapered toward one end.

One object is to supply steam more or less rarefied to one or both surfaces of the garment or of an intervening fabric just before the application of pressure.

In apparatus of this character, as in my pending application referred to, it has been customary to make either or both of the pressing elements in the form of hollow cast metal plates for forming internal steam chambers, the upper pressing element or head being usually provided with a foraminous bottom for distributing the steam evenly over the surface of the garment while under pressure.

The main object, therefore, of my present invention is to do away with the foraminous presser face for the passage of steam onto the garment while under pressure and substituting therefor comparatively small steam conduits running around the marginal edge or edges of one or both of the pressing elements and providing such conduits with branch passages arranged so as to direct the steam inwardly across the contiguous faces of said elements or between the pressing faces and surface of the garment, conditioning the garment thereby for the action of the pressing element which may be either of

smooth metal or covered by screening fabric as desired to give character to the work, steam being directed either to moisten the garment or to moisten the fabric as desired.

Other objects and uses will be brought out in the following description.

In the drawings—Figure 1 is a perspective view, partly in section, of a portion of a garment pressing machine embodying the features of my invention. Fig. 2 is an enlarged front elevation, partly in section, of the buck and press head showing portions of their supports. Fig. 3 is a transverse sectional view of a buck and press head similar to that shown in Figs. 1 and 2 except that the steam conduits are made separately from and seated upon or against the marginal edges of the pressing elements and connected with inwardly extending branch passages. Figs. 4 and 5 are respectively a top plan of a slightly modified buck and an inverted plan of a similarly modified press-head, the metal screen being removed. Fig. 6 is an enlarged transverse sectional view of the head shown in Fig. 5.

This machine comprises a buck —1— and a press head —2—, the buck being mounted upon a suitable supporting bracket —3— while the press head is mounted upon a rocking frame —4— which is hinged upon a suitable supporting rod —5— at the rear of the pressing elements in the manner shown in U. S. patent to A. J. Hoffman, No. 928,199, July 13, 1909, so as to enable the press head to be moved vertically to and from the buck somewhat in the manner set forth in my pending application referred to. These pressing elements preferably consist of cast metal plates of substantially the same form and area and are preferably elongated in one direction and tapered toward one end and provided with rounding ends, the area of the meeting faces being sufficient to press trousers, skirts, coats and similar garments throughout their entire lengths in a single operation.

One or both, in this instance both, of the pressing elements are provided with steam conduits —6— running entirely around their marginal edges and are also provided with branch ducts —7— leading inwardly from the ducts —6— between the adjacent surfaces of the press-plates and arranged at short intervals throughout the lengths of the main conduits —6— in the manner

shown in Figs. 4 and 5 so as to diffuse the steam as evenly as possible across the entire surface of said plates. As a further means for distributing or diffusing the steam over the surface or surfaces of a garment while under mechanical pressure the meeting faces of the press-plates may be provided with a series of transverse grooves —12— and lengthwise grooves —13— intersecting each other so that the steam entering one set of grooves may readily pass into those of the other set and thereby spread over practically the entire surfaces of the buck and press head. The branch ducts of the main steam conduits are registered as nearly as possible with the adjacent ends of the distributing grooves to permit free passage of the steam into such grooves.

The presser faces and inner ends of the ducts —7— may be covered by a fine wire screen —8— of copper, brass or similar tenacious or flexible metal which serves to give a dull finish to the surface of the garment under pressure and at the same time aids in distributing the steam evenly over the surface of such garment, thereby imparting a slight amount of moisture to the contiguous surface of the garment. As previously intimated, steam is usually introduced under high pressure and it is therefore more or less rarefied so as to reduce the amount of moisture content, thereby avoiding as far as practicable excessive accumulations of moisture and owing to the heated condition of the pressing elements expedites the drying of the garment while under pressure. The marginal edges of the wire screens are drawn tightly around the marginal edges of the pressing elements and engaged with suitable pins or studs —9— to hold them in operative position.

Steam may be supplied to the conduit —6— from any available source through suitable pipes —10— which are connected to said conduits wherever desired to produce the desired distribution of steam throughout the entire lengths of the conduits. These supply pipes are provided with normally closed valves —11— adapted 50 to be opened by hand when necessary to

admit steam to the garment, usually just before the pressing elements are in their pressing position.

In Figs. 4 and 5 I have shown a buck —14— and press head —15— as having their meeting faces provided with transverse grooves —12— and lengthwise grooves —13— intersecting each other, the transverse grooves —12— extending to the outer edges of the pressing elements where they communicate with steam supply conduits —16— and —17—. These conduits are preferably secured to the opposite lengthwise edges of both pressing elements by suitable fastening means as bolts —18— and are provided with branch passages —19— which register with the adjacent ends of the transverse grooves to distribute the steam over as large an area as possible.

What I claim is:

1. In a garment pressing machine, two co-acting pressing elements provided with impervious presser faces, one of which elements is movable toward and from the other; a conduit running along the marginal edge of one of said elements and provided with lateral branch passages directing steam across the presser face of such element.

2. In a garment pressing machine a buck; an impervious press plate movable toward and from the buck; a conduit running entirely around the press plate and provided with branch passages extending inwardly across the lower surface of the press plate; and a screen covering the inner face of said press plate.

3. In a garment pressing machine, two pressing elements, consisting of metal plates having their marginal edges provided with steam conduits having branch passages extending laterally across the pressing faces of said plates, and a metal screen covering the meeting faces of said plates.

In witness whereof I have hereunto set my hand on this 19th day of January 1911.

THEODORE D. PALMER.
